UNITED STATES PATENT OFFICE.

RUDOLF NOSKE, OF SAN FRANCISCO, CALIFORNIA.

TELESCOPE-SIGHT MOUNTING.

Application filed November 3, 1921. Serial No. 513,386.

To all whom it may concern:

Be it known that I, RUDOLF NOSKE, a citizen of the United States, residing in the city and county of San Francisco and State of California, have invented a new and useful Improvement in a Telescope-Sight Mounting, of which the following is a specification.

My invention relates to improvements in mountings for telescope sights for rifles and the like.

The primary object of my invention is to provide an improved mounting for telescope sights for rifles.

Another object is to provide improved locking means adapted to hold a telescope rigidly in operative position while the rifle is in use.

Another object is to provide an improved locking means adapted to facilitate the placing and removing of a telescope sight upon a rifle.

A further object is to provide an improved mounting means for preventing transverse or lateral movement of the sight when the rifle is fired.

Another object is to provide an improved mounting having means adapted to facilitate the adjusting of a telescope sight laterally to compensate for windage.

A further object is to provide an improved locking means adapted to compensate for wear to insure against loosening of the sight.

A still further object is to provide improved means for limiting the movement of the locking pin to facilitate removal of the movable mounting when the sight is to be removed from the rifle, and to prevent loss of parts.

I accomplish these and other objects by means of the device disclosed in the drawings forming a part of the present specification wherein like characters of reference are used to designate similar parts throughout said specification and drawings, and in which—

Fig. 1 is a broken plan view of a rifle equipped with a telescope sight secured by my improved mounting.

Fig. 2 is a broken side elevation of Fig. 1.

Fig. 3 is a side elevation of my improved mounting shown upon a larger scale.

Fig. 4 is a plan view of Fig. 3.

Fig. 5 is a rear elevation of the mounting.

Fig. 6 is a transverse section taken on line 6—6 of Fig. 3 in the direction indicated.

Referring to the drawings the numeral 1 is used in general to designate a stationary mounting plate arranged to be screwed or otherwise secured upon the breech 2 of a rifle 3. A dovetail 4 is formed upon the upper edge of the plate 1 and a tapered groove 6 is formed upon the surface of the dovetail.

A movable plate 7 is provided with a dovetail slot 8 in the bottom surface thereof to slidably engage the dovetail 4 of the stationary plate 1 and a telescope receiving member 9 is pivotally mounted upon the movable plate 7 by means of a screw 11 or other suitable pivot, the free end of the member 9 abutting against an upwardly extending lug 12 upon the plate 7, the proximate surfaces of the lug 12 and the member 9 being made arcuate in shape to permit pivotal movement of the member 9 about the pivot 11, said lug operating to relieve the pivot from stress due to inertia of the telescope and the mounting when the rifle is fired.

A pair of telescope supporting elements 13 are formed integral with the member 9, said elements 13 being arranged in spaced relation to form a firm supporting base for a telescope sight 14. A pair of clamping elements 16 adapted to fit over the telescope when supported on the elements 13 are apertured at the ends to receive screws 17 adapted to be screwed into the elements whereby said telescope may be firmly clamped in position upon the member 9 and hence upon the movable plate 7.

A pair of adjusting screws 18 are threaded into the lug 12 and arranged to bear upon a shoulder 19 formed upon the free end of the member 9 from opposite sides thereof whereby said member 9 may be secured in fixed lateral position with respect to the lug 12 and the member 9. The member 9 may be adjusted laterally to compensate for windage and the like, by loosening the screw 18 upon one side of the lug 12, and tightening the other screw a corresponding amount so as to engage the shoulder 19 and hold the same in rigid position in the corrected position. It is obvious that correction may be made toward either side of the mounting as the requirement may be. A plurality of calibrations 21 are preferably

made upon one of the screws 18 whereby the amount of correction may be gaged, said calibrations being graduated to give a definite correction at a defined distance, any 5 fixed point upon the mounting serving as an index from which the amount of rotation may be gaged.

The shoulder 19 is fitted into a corresponding groove 22 in the lug 12 thereby serving 10 the additional purpose of preventing vertical movement of the free end of the member 9.

One of the principal difficulties to be met 15 in mounting a telescope sight upon a rifle is to provide a rigid locking means for preventing movement of the telescope and mounting due to inertia when the rifle is fired, the stresses caused in this way being so great as to shear and batter the ordinary 20 securing means within a comparatively short time to such an extent as to render the mounting and sight useless. As previously stated one of my chief objects is to provide an improved locking means which is adapted to 25 withstand such stresses and hold the sight and movable mounting plate in rigid position when mounted for use. I accomplish this in the following improved manner:

An extension 25 is formed integrally with 30 or secured upon one side of the movable plate 7 and a centrally disposed bore 26 formed therein, said bore extending through the plate 7 and intersecting the dovetail slot 8 and forming a groove 27 thereacross, said 35 bore 26 being positioned so that the groove 27 will match with the tapered groove 6 in the dovetail 4.

A locking pin 28 is slidably mounted within the bore 26, the forward end 29 of the pin 40 being beveled at the inclination of the tapered groove 6. A reduced portion 31 is formed at the other end of the pin 28 to form a shoulder 32, and a notch 33 is formed in one side of the pin 28.

45 A nut 34 is threaded onto the extension 26, an internal annular shoulder 36 being provided at one end of said nut to engage the shoulder 32 of the pin 28 and to permit passage of the reduced portion 31 there- 50 through. The end of the reduced portion 32 is apertured to receive a cotter pin 35 adapted to normally hold the shoulder 36 of the nut in engagement with the shoulder 32 of the pin.

55 A transverse slot 37 is formed upon the extension 26 near the outer end thereof to receive a transversely disposed key 38 preferably made semicircular in shape and adapted to be inserted through the slot 37 60 into engagement with the notch 33 formed upon the side of the pin 28. The semicircular side of the key 38 matches with the bottom of one of the threads of the extension 26 and the flat side of the key rests upon the 65 bottom of the notch, said notch being made

of sufficient length to permit the desired amount of movement of the pin 28.

My improved locking means is assembled by inserting the pin 28 into the bore 26 with the notch 33 adjacent the slot 37. The key 70 38 is then inserted and the nut 34 applied thereover, said nut being advanced upon the extension 25 until the shoulders 36 and 32 are brought into engagement and the cotter pin 35 is inserted to hold said collars in 75 engaging relation. The operation of the locking means is as follows:

The movable plate 7 being positioned upon the stationary plate 1 so that the grooves 6 and 27 will be in matching relation, the nut 80 34 is advanced along the extension 25, the shoulder 36 thereby moving the pin 28 into the recess formed by said grooves. A continued advance of the nut will cause the beveled end of the pin 28 to be moved in binding relation with the tapered groove 6, the pin, operating as a wedge, is rigidly bound between the movable and stationary plates. The pin also tends to lift the movable plate so that the dovetail 4 will be in binding relation with the movable plate, along the entire 90 length of the dovetail slot 8, in this manner increasing resistance to displacement and relieving the pin 28 of the greater part of the shearing stress to which it would be 95 otherwise subjected.

When it is desired to remove the movable mounting to dismount the sight, the nut 34 is loosened, the cotter pin 35 causing the locking pin 28 to be receded to disengage 100 and release the mounting plates, as shown in dotted lines in Fig. 6 of the drawings. The key 38 engages the forward end of the notch 33 before the nut is entirely removed from the extension 25 thereby preventing 105 further movement of the nut or the pin 28 and insuring against loss of any part while the sight is dismounted.

My improved locking means will remain effective even after long usage as any wear 110 that occurs will be upon the beveled end of the pin 28, and by virtue of the tapered groove 6 and the beveled end 29 such wear will be readily taken up and compensated for by advancing the pin a correspondingly 115 greater distance into the recess between the grooves 6 and 27.

A screw 41 is placed at the rearward end of the movable plate 7 to engage the end of the fixed plate 1 to facilitate the aligning of 120 the ends of said plates in which position the grooves 6 and 27 are preferably caused to be in matching position.

Having thus described my invention what I claim as new and desire to secure by Let- 125 ters Patent is:

1. A mounting for telescope sights for rifles and the like comprising a stationary mounting plate having a groove in the top thereof and arranged to be secured upon the 130

- breech of a rifle; a movable mounting plate mounted upon said stationary plate, said movable plate having a transversely disposed groove matching with the groove formed in 5 the top of the stationary plate; a pin slidably mounted between said matching grooves; and means for moving said pin into locking engagement between the plates to rigidly secure the movable plate against 10 longitudinal movement when in use.
2. A mounting for telescope sights for rifles and the like comprising a stationary mounting plate having a tapered groove in the top thereof and arranged to be secured upon the breech of a rifle; a movable mounting plate mounted upon said stationary plate, said movable plate having a transversely disposed groove matching with the tapered groove formed in the stationary 15 plate; a pin slidably mounted between said matching grooves, one end of the pin being beveled to match the tapered groove; and means for moving said pin into locking engagement between the plates to rigidly secure the movable plate against longitudinal movement when in use.
3. A mounting for telescope sights for rifles and the like comprising a stationary mounting plate arranged to be mounted upon 20 the breech of a rifle; a movable mounting plate mounted upon said stationary plate; a telescope receiving member pivotally mounted upon said movable member; means for securing a telescope sight upon said receiving member; means for moving said telescope receiving member laterally about its pivot connection to obtain lateral adjustment of the sight; and means for rigidly securing the movable member upon the stationary plate.
4. A mounting for telescope sights for rifles and the like comprising a stationary mounting plate arranged to be secured upon the breech of a rifle, said plate being provided with a dovetail upon the upper edge thereof, said dovetail having a tapered groove formed transversely thereon; a movable member having a dovetail slot adapted for engagement with dovetail upon the stationary plate, said member having a groove matching with the tapered groove of said dovetail; a pin slidably mounted to engage said grooves, said pin having a beveled end arranged to engage said tapered groove; 55 means for moving said pin into locking position between the movable and fixed plates to lock the same against relative movement; a telescope receiving member pivotally mounted at one end thereof upon the movable plate; means for securing a telescope sight upon the receiving member; and means for moving said receiving member laterally about its pivotal connection to obtain lateral adjustment of the sight.
5. A telescope sight mounting comprising a stationary mounting plate provided with a dovetail having a tapered groove thereon; a removable mounting plate having a dovetail slot slidably engaging said dovetail, said removable plate being provided with a lateral extension having a bore extending through the removable member and intersecting the dovetail slot to form a groove matching with the tapered groove of the dovetail; a pin slidably mounted within said extension, said pin being beveled at one end thereof and having a notch formed in one side thereof; a nut threaded upon the lateral extension and arranged to engage the end of the pin for moving said pin within the extension into locking position in engagement with the grooves between the stationary and movable plates; and means mounted upon the extension and engaging the notch in the side of the pin for limiting the movement of the pin and normally preventing removal of the nut.
6. The combination with a telescope mounting comprising a stationary plate having a groove in the top thereof and a movable plate slidably mounted upon said stationary plate and having a groove matching with the groove on the stationary plate, said movable plate having a threaded extension on one side thereof, of a locking pin slidably mounted within said extension and arranged to be advanced into locking position in engagement with the matching grooves formed in the plates, said locking pin having a notch formed upon one side thereof; a nut mounted upon the threaded extension to engage one end of the pin for moving the same into and out of engagement with the grooves; and a key mounted within the extension in engagement with the notch upon the pin for limiting the rearward movement of said pin.

In witness whereof I hereunto set my signature.

RUDOLF NOSKE.
